R. N. FERGUSON

EXPANDING ROTARY BIT

Filed Oct. 24, 1923

UNITED STATES PATENT OFFICE.

ROY N. FERGUSON, OF LOS ANGELES, CALIFORNIA.

EXPANDING ROTARY BIT.

Application filed October 24, 1923. Serial No. 670,507.

My invention relates to the art of drilling oil wells, and is particularly applicable to the rotary system of drilling.

It is many times highly desirable in rotary drilling to be able to "carry" pipe, both for the purpose of holding up the walls of the well and for the purpose of controlling and directing the water circulation of the well. When pipe is so carried, it is necessary to employ a rotary bit which will pass through the pipe and which will cut a hole larger in diameter than the pipe.

It is an object of my invention to provide such a bit.

15 The wear on rotary bits is very great and it is a further object of my invention to provide a bit having removable arcuate cutters which can be readily replaced.

It is a still further object of my invention 20 to provide a bit with rotary cutters which are easily fabricated.

Since rotary bits are subjected to very heavy stresses, it is a further object of my invention to provide a bit which is very 25 rugged and strong.

Further objects and advantages will be made evident hereinafter.

Referring to the drawing which is for 30 illustrative purposes only,

Fig. 1 is a side edge elevation of a bit embodying my invention.

Fig. 2 is a side elevation of the same bit embodying my invention.

Fig. 3 is a view of the bit as seen from 35 below.

Fig. 4 is a vertical sectional view taken on the line 4-4 of Fig. 1.

In the form of the invention illustrated, I employ a body 11 which is provided with 40 a threaded pin 12 adapted to fit into a rotary tool joint.

Projecting downwardly from the body 11 are two legs 13, having an opening 14 therebetween. A water passage 16 extends downwardly between the legs and communicates with the space 14. A pin 20 having a head 21 at one end passes between the legs, being threaded at the other end to engage a nut 22. Mounted on the pin 20 between the legs 13 are cutting discs 23, these 45 discs being circular in contour and having

a hole for the pin 20 eccentrically placed therein. The discs are shown in their cutting position in full lines in Fig. 2 and in their retracted position in dotted lines in that figure. It will be observed that the eccentric mounting of the discs is so designed that when they are in their cutting position the axis of the pin 20 is slightly lower than the longitudinal axes of the discs. The object achieved by this is that any hard formation 55 on the side of the hole exerting a horizontal thrust in resistance to its abrasion will positively lock the discs in their expanded position and assure a hole of even diameter. The lower edges of the discs, when in the 60 cutting position, are provided with a sharp edge 25. The opening 14 is shaped to provide an upper curved abutment face 14' on each side of the body against which the upper portions of the respective discs may abut 65 when in their expanded positions. The opening 14 is further defined by curved engagement faces 15, one on each side of the body. These engagement faces are adapted to be engaged by the discs when in retracted 70 position and serve to prevent undesirable swinging of the discs or cramping of the discs in the wrong positions.

75 The method of operation is as follows:

When it is desired to run the bit into the 80 hole, the discs are turned into the position shown in dotted lines in Fig. 2, and may then be run down through the pipe which it is desired to underream. Whenever the discs strike the bottom of the hole, they turn 85 into the position shown in full lines in Fig. 2, being thereby expanded to cut a hole large enough to allow the pipe to pass downwardly. The rotary mud is circulated 90 through the opening 16 in the ordinary manner, or special types of circulation or circulating medium may be employed.

I claim as my invention:

In a rotary bit, the combination of: a 95 body; a pair of spaced legs extending downward from said body, a pair of abutment faces being formed between said legs, and a pair of engagement faces being formed on said body between said legs; a pin secured to said legs; and a pair of cutting discs ec- 100

centrically mounted on said pin between said legs in such a manner as to have a retracted position and an expanded cutting position, the peripheries of said discs being adapted to engage said engagement faces when said discs are in retracted positions and to engage said abutment faces when in

expanded positions, the longitudinal axes of said discs being above the axis of said pin when said discs are fully expanded.

In testimony whereof, I have hereunto set my hand at Los Angeles, California, this 18th day of October, 1923.

ROY N. FERGUSON.
